U.S. CL. 252—90

6 Claims

ABSTRACT OF THE DISCLOSURE

Pre-electric shave composition and process for shaving utilizing same whereby improved skin lubrication is obtained, said composition being a self-propelled, quick-breaking foam comprising (a) a cosmetic absorbent powder, (b) an aqueous alcoholic carrier medium, (c) a surfactant being a member of the group of ethoxylated fatty acids or alcohols, glycerol and polyglycerol esters of fatty acids and certain cationic pyridinium compounds, and (d) an aerosol propellant.

This invention relates to pre-electric shave compositions and a process for shaving using said compositions. More particularly, this invention relates to pressurized pre-electric shaving compositions containing a cosmetic absorbent powder which is incorporated in a self-propelled, quick-breaking foam enabling a uniform and even deposition of lubricants to be spread out on the skin.

Any shaving employing an electric razor requires that the skin be dry and substantially free from dirt and sebaceous surface discharges such as waxes, oils and salt. The attainment of these objectives by heretofore known pre-electric shave compositions has not been fully satisfactorily accomplished, and, in many cases, those employing an electric razor experience a serious skin irritation. For these reasons, dry electric shaving has not met with the widest possible acceptance.

Heretofore known pre-electric shave compositions have generally been of two types: The alcoholic type, and the dry stick type. Both preparations have serious disadvantages. The alcoholic preparations do leave the skin dry but fail to absorb the epidermal oil or salt so that complete lubrication is not achieved. The dry stick type, exemplified by talc-binder stick preparations, is both difficult to apply and spread evenly on the skin and the powder does not adhere to the skin and flakes off, thereby soiling clothing and the area below where the talc is applied.

Accordingly, it is an object of this invention to provide an absorbent powder-containing pre-electric shave composition enabling the powder to be evenly and easily applied to the skin of the user.

Another object is to provide a process for shaving with an electric razor wherein the skin is more effectively lubricated and simultaneously dirt, epidermal wax, oils, salt and moisture are removed from the skin so as to improve the efficacy of the razor.

In accordance with this invention, there have been discovered pressurized, pre-electric shave compositions in the form of self-propelled foams which are quick-breaking when applied to the skin, comprising the following ingredients in percentages by weight of the overall composition:

(a) From about 5 to 25% of a cosmetic absorbent powder having a particle size of from about 1 to 25 microns;

(b) From about 60 to 90% of an aqueous alcoholic carrier medium for said powder, said alcohol being a C₁—C₆ monohydric alkanol and the weight ratio of said alkanol to water in said carrier medium being from about 3:1 to 1:3;

2

(c) From about 0.5 to 5% of a surfactant which is difficultly soluble or substantially insoluble in said aqueous alcoholic carrier medium and being a member selected from the group consisting of:

5 (i) Condensates of 1 to 3 mols of ethylene oxide with 1 mol of C₁₀ to C₂₀ aliphatic monohydric alcohols; and admixtures of C₁₆ to C₁₈ aliphatic monohydric alcohols with condensates of 4 to 20 mols of ethylene oxide with 1 mol of said C₁₀ to C₂₀ alcohols;

10 (ii) Condensates of 1 to 3 mols of ethylene oxide with 1 mol of C₁₀ to C₂₀ fatty acids; and admixtures of C₁₆ to C₁₈ aliphatic monohydric alcohols with condensates of 4 to 20 mols of ethylene oxide with 1 mol of C₁₀ to C₂₀ fatty acids;

15 (iii) Esters of C₁₆ to C₁₈ fatty acids with glycerol and the dimeric to hexameric polyglycerols; and

(iv) Long chain cationic quaternary pyridinium compounds having the formula

wherein R represents alkyl and alkenyl radicals having 15 to 17 carbon atoms; and

25 20 (d) From about 5 to 30% of a propellant being a member selected from the group consisting of lower alkanes and alkyl chlorides having up to 5 carbon atoms and fluorinated and fluorochlorinated alkanes having at least one fluorine atom and not more than 2 carbon atoms.

30 25 This invention further contemplates a process for dry shaving employing the aforesaid composition by applying it to the skin in the form of a foam which breaks quickly when applied to the skin, allowing the composition to dry on the skin whereby said cosmetic absorbent powder is evenly and uniformly distributed over the skin and adheres to the skin without flaking off and absorbs sebaceous discharges, salt, moisture and dirt and thereafter removing the unwanted hair with an electric razor.

35 30 The cosmetic absorbent powder employed in the compositions of the present invention should have a particle size in the range of about 1 to 25 microns and, most suitably and preferably, from about 5 to 15 microns.

40 35 The term "absorbent powder" as used herein is meant to describe those suitable cosmetic powders exemplified by those hereinbelow described which have both absorbent and adsorbent qualities for the purpose of economy of language, as well as for the reason that it is not known in all cases whether the particles act as absorbers or adsorbers or both. The precise mechanism of their function in acting as a lubricant is not a critical aspect of this invention.

45 40 Suitable absorbent powders are exemplified by talc, which is a hydrated magnesium silicate, clays such as kaolin, a hydrated aluminum silicate, and diatomaceous earth, the carbonates such as calcium carbonate and magnesium carbonate, metallic stearates such as magnesium stearate and zinc stearate, oxides such as zinc oxide and titanium oxide, silica, silica gels, alumina and the like, as well as various blends and admixtures of the aforesaid. Other cosmetically suitable absorbent powders will be apparent to those skilled in the art and the invention is not to be considered as being limited to any one particular absorbent powder or combination of absorbents.

50 45 Talc is a particularly preferred absorbent powder because of its excellent lubricating, absorptive, skin adherence and counter-irritant qualities.

55 50 The amount of cosmetic absorbent powder employed in the compositions of the present invention will vary from about 5 to 25% by weight and preferably in the range of from about 15 to 20% by weight of the overall composition.

The aqueous alcoholic carrier employed in the compositions of the present invention functions as a medium for the dispersion of the absorbent powder as well as contributing to the highly desirable characteristics of the compositions of the present invention, i.e., a self-propelled, quick-breaking foam.

This hydroalcoholic admixture will generally be present in an amount of from about 60 to 90% by weight of the overall composition with the weight ratio of alcohol to water being from about 3:1 to 1:3. It has been found that maintenance of this weight ratio is important for the achievement of optimum dispersion of the absorbent powder and retention of the quick-breaking characteristics of the foam. Preferably, there will be employed from about 65 to 75% by weight of hydroalcoholic carrier with the aforesaid ratio being from about 1.5:1 to 2:1. Suitable alcohols include the C_1 to C_6 monohydric alkanols. Ethanol and isopropanol are particularly preferred alkanols. Other suitable alkanols are methanol, butanol and isobutanol, propanol, amyl alcohol, hexyl alcohol and various isomers thereof.

The surfactants employed in the compositions of the present invention should be substantially insoluble or difficultly soluble, i.e., to an extent not greater than about 10% by weight and, preferably, not greater than 5% by weight, in the aqueous alcoholic carrier medium and at the same time be dispersible throughout the system, otherwise the desired quick-breaking characteristics of the self-propelled foam are not attained. While a great number of anionic, cationic and nonionic surfactants will have the desired hydrophobic characteristics and will lend themselves to be compatible with the compositions of the present invention, the surfactants hereinafter described in detail have been found to be extremely valuable in formulating the compositions of the present invention.

Suitable surfactants include the ethers of long chain alcohols which may be described as the condensation products of 1 to 3 mols of ethylene oxide with 1 mol of C_{10} to C_{20} straight and branched chain aliphatic monohydric alcohols as exemplified by fatty alcohols such as decyl alcohol, lauryl alcohol, myristyl, cetyl and stearyl alcohols, unsaturated fatty alcohols such as oleyl and linoleyl alcohols, Oxo alcohols prepared by the catalytic reaction of a polyolefin with carbon monoxide and hydrogen and subsequent reduction such as Oxo tridecyl alcohol, Oxo pentadecyl alcohol and Oxo hexadecyl alcohol. The aforesaid C_{10} to C_{20} aliphatic monohydric alcohols may be ethoxylated with more than 3 mols of ethylene oxide, up to about 20 mols of ethylene oxide being suitable. However, in order to impart the desired characteristic of substantial insolubility in the hydroalcoholic medium, these 4 to 20 mol ethylene oxide adducts are employed in admixture with from 10 to 50% by weight of a C_{16} to C_{18} aliphatic monohydric alcohol, preferably a straight chain C_{16} to C_{18} fatty alcohol such as cetyl alcohol.

Also suitable as the surfactant component in the compositions of the present invention are condensates of C_{10} to C_{20} fatty acids with 1 to 3 mols of ethylene oxide, as well as admixtures of the 4 to 20 mol ethylene oxide adducts of said acids with from 10 to 50% by weight of a C_{16} to C_{18} aliphatic monohydric alcohol. Exemplary fatty acids, which may be condensed with ethylene oxide to form surfactants suitable herein, are capric, lauric, myristic, palmitic, stearic, oleic and linoleic acids, as well as mixtures of such acids as exemplified by tall oil fatty acids, coconut acids and the like.

Additionally, suitable as surfactants are the esters of C_{16} to C_{18} fatty acids with glycerol and dimeric to hexameric polyglycerols. Exemplary are glycerol monostearate, glycerol monooleate, glycerol monopalmitate, diglycerol monostearate and monooleate, triglycerol monopalmitate, trimethylol propane (hexaglycerol) monooleate and similar polyglycerol esters.

The cationic quaternary pyridinium surfactants which are suitable for use in the compositions of the present invention are best described by the general formula

wherein R represents alkyl and alkenyl radicals having from 15 to 17 carbon atoms. They may be prepared, for example, as described in U.S. Patent No. 2,189,664. Exemplary and particularly preferred is the compound commonly referred to as stearoyl colamino formyl methyl pyridinium chloride, R being an alkyl chain of 17 carbon atoms.

Compositions of the present invention containing the aforesaid cationic surfactants are particularly preferred embodiments, since it has been found that these quaternary pyridinium compounds allow better adhesion of the absorbent powder to the skin, a more uniform dispersion of absorbent powder in the foam, as well as imparting a desirable emollient after-feel to the skin once shaving has been completed.

The aforesaid surfactants are employed in amounts ranging from 0.5 to 5% by weight, and preferably within the range of about 1 to 3% by weight. Also, it is suitable to employ mixtures of the aforesaid surfactants, especially mixtures of said cationic pyridinium compounds with said fatty acid ethylene oxide condensates.

The propellents suitable for use herein are, per se, well known and comprise the lower alkanes and isomers thereof containing up to 5 carbon atoms such as butane, pentane and isobutane, propane and the like, or lower alkyl chlorides having up to 5 carbon atoms such as methyl, ethyl or propyl chlorides. The most suitable liquid propellents are the fluorinated and fluorochlorinated lower alkanes containing at least one fluorine atom and not more than two carbon atoms such as dichlorodifluoromethane, dichlorotetrafluoroethane, trichloromonofluoromethane, dichloromonofluoromethane, monochlorodifluoromethane, difluoroethane, trichlorotrifluoroethane and the like. The propellant will be employed in amounts ranging from 5 to 30% and, preferably, within the range of 10 to 30% by weight of the overall composition.

Numerous special purpose additives may be added to the compositions of the present invention in small proportions without adversely affecting the stability of the overall composition. Such materials include, for example, perfumes, viscosity modifying agents, emollients, skin conditioning agents or lubricants such as the silicone fluids, medicaments, and the like. Exemplary materials include glycerol, sorbitol, propylene glycol, lanolin, chlorinated phenolic antiseptics such as hexachlorophene, menthol, camphor and other skin coolants.

The compositions of the present invention may be prepared by first dispersing the absorbent powder, under conditions of moderate agitation, into an admixture of hydroalcoholic carrier and surfactant, and thereafter charging the composition with propellant into an aerosol dispensing vessel employing conventional techniques used in aerosol packaging. This mode of preparation, while recommended for optimum results, may be varied as desired without any deleterious effect upon the suitability of the finished product.

In utilizing the compositions of the present invention in dry electric shaving, the self-propelled material is dispensed from the vessel as a foam which breaks quickly as it is applied to the skin. The composition is allowed to dry and the absorbent powder becomes uniformly and evenly distributed over the skin and exhibits excellent adherence to the skin. Sebaceous, oily and waxy discharges, moisture, salt and dirt are transferred to the absorbent and an electric shaver is then employed to remove unwanted hair. A complete absence of skin irritation is

noted, and upon completion of shaving, the user experiences a pleasant after-feel in the shaved area.

The invention is further illustrated by the following examples which are not to be considered as limitative of its scope. All percentages given are by weight, based on the weight of the overall composition.

EXAMPLE I

The following composition is prepared for use in a self-propelled pressurized container:

	Percent
Talc (10-15 microns)	20.0
Ethanol	38.8
Water	28.2
Condensate of 4 mols of ethylene oxide with 1 mol of stearic acid admixed with 50% by weight cetyl alcohol (surfactant)	3.0
Propellant (a 40:60 blend of dichloro-difluoromethane and dichlorotetra-fluoroethane)	10.0

The composition is prepared by dispersing the talc particles with moderate agitation into an admixture of the ethanol, water and the surfactant. The composition is charged with propellant into suitable dispenser fitted with a valve for dispensing pressurized compositions. The composition is then ready for use. A quantity is discharged as foam and applied to the face. Upon application to the face, the foam immediately breaks and the composition is allowed to dry on the face. An electric razor is activated and unwanted hair is quickly and easily removed. The user experiences no skin irritation and a pleasant after-feel on the face is noted.

EXAMPLE II

The composition of Example I is prepared except that 28% water, 40% ethanol, 2.0% glycerol monostearate with no cetyl alcohol added are employed. Equivalent results are obtained.

EXAMPLE III

The following composition is prepared in the manner of Example I:

	Percent
Talc (10-15 microns)	20.0
Ethanol	40.0
Water	28.2
Stearoyl colamino formyl methyl pyridinium chloride	1.6
Perfume	0.2
Propellant of Example I	10.0

This example illustrates the use of a quaternary pyridinium emulsifier. Again, excellent shaving results are obtained after applying the composition to the face as a quick-breaking foam. The user also experiences a pleasant after-feel on the skin.

The compositions set forth in Examples IV to VII are prepared as in the manner of Example I and in each case excellent results are obtained.

EXAMPLE IV

	Percent
Talc (10-15 microns)	18.0
Isopropanol	25.2
Ethanol	17.5
Water	26.5
Condensate of 1 mol of oleic acid with 20 mols of ethylene oxide admixed with 50% by weight cetyl alcohol	1.5
Stearoyl colamino formyl methyl pyridinium chloride	1.3
Propellant of Example I	10.0

EXAMPLE V

	Percent
Kaolin clay (10-25 microns)	30.0
Ethanol	36.0
Water	24.0
Condensate of 3 mols of ethylene oxide with 1 mol of lauryl alcohol	1.00
Propellant of Example I	9.00

EXAMPLE VI

Example V is repeated except that diatomaceous earth is employed in place of clay.

EXAMPLE VII

	Percent
Talc	20.00
Zinc oxide	2.00
Isopropanol	22.00
Ethanol	22.00
Water	27.5
Triglycerol monostearate	1.5
Propellant (84% isobutane, 16% propane)	5.0

What is claimed is:

- 25 1. A self-propelled quick-breaking, pre-electric shave foam composition which consists essentially of the following ingredients in percentages by weight of the overall composition:
  - (a) from about 5 to 25% of a cosmetic absorbent powder having a particle size of from about 1 to 25 microns;
  - (b) from about 60 to 90% by weight of an aqueous alcoholic carrier medium for said powder, said alcohol being a C_1 - C_6 monohydric alkanol and weight ratio of said alkanol to water in said carrier medium being from about 3:1 to 1:3;
  - (c) from about 0.5 to 5% by weight of a surfactant which is substantially insoluble in said aqueous alcoholic carrier medium of being a member selected from the group consisting of
    - (i) condensates of 1 to 3 mols of ethylene oxide with 1 mol of C_{10} to C_{20} aliphatic monohydric alcohols;
    - (ii) condensates of 1 to 3 mols of ethylene oxide with 1 mol of C_{10} to C_{20} fatty acids;
    - (iii) esters of C_{16} to C_{18} fatty acids with glycerol and the dimeric to hexameric polyglycerols; and
    - (iv) long chain cationic quaternary pyridinium compounds having the formula

wherein R represents alkyl and alkenyl radicals having 15 to 17 carbon atoms, said surfactant being present in an amount of from about 0.5 to 5.0% by weight; and

- 55 (d) from about 5 to 30% of a propellant being a member selected from the group consisting of lower alkanes and alkyl chlorides having up to 5 carbon atoms and fluorinated and fluorochlorinated alkanes having at least one fluorine atom and not more than 2 carbon atoms.
- 60 2. A composition according to claim 1 wherein said cosmetic absorbent powder is talc.
- 65 3. A composition according to claim 1 wherein said surfactant corresponds to ingredient (c)(iv) and wherein said R is an alkyl radical having 17 carbon atoms.

4. A composition according to claim 1 wherein said C₁-C₆ monohydric alkanol is ethanol and said weight ratio of said ethanol to said water is from about 1.5:1 to 2:1.

5. A composition according to claim 1 wherein said ingredients are present in the following percentages by weight:

10 said (a) ingredient, from 15 to 20%,
said (b) ingredient, from 65 to 75%,
said (c) ingredient, from 1 to 3%,
said (d) ingredient, from 10 to 30%.

15 6. A process for removing unwanted hair from the skin comprising applying to the skin the pre-electric shave foam composition of claim 1, allowing said composition to dry on the skin whereby said absorbent powder is highly evenly distributed over the skin, and removing said unwanted hair using an electric shaver.
